(57) **CLAIM**

The ornamental design for display screen or portion thereof with an animated graphical user interface, as shown and described.

DESCRIPTION

FIG. 1 is the front view of the first image in a sequence for a display screen or portion thereof with an animated graphical user interface;

FIG. 2 is the second image thereof;

FIG. 3 is the third image thereof;

FIG. 4 is the fourth image thereof;

FIG. 5 is the fifth image thereof;

FIG. 6 is the sixth image thereof; and,

FIG. 7 is the seventh image thereof.

The process or period by which one image transitions to another forms no part of the claimed design.

1 Claim, 7 Drawing Sheets
